(57) CLAIM

The ornamental design for a handbag, as shown and described.

DESCRIPTION

The patent or application file contains at least one photograph executed in color. Copies of this patent or patent application publication with color photograph(s) will be provided by the Office upon request and payment of the necessary fee.

FIG. 1 is a front left perspective view of a handbag showing my new design;

FIG. 2 is a front elevation view where the interior drawstring liner and drawstring are in an alternate condition of use;

FIG. 3 is a rear elevation view of the alternate condition shown in FIG. 2;

FIG. 4 is a left side view thereof;

FIG. 5 is a right side view thereof;

FIG. 6 is a top plan view thereof; and,

FIG. 7 is a bottom view thereof.
